CLAIM

The ornamental design for a tire, as shown and described.

DESCRIPTION

FIG. 1 is a perspective view of a first embodiment of a tire of our new design, it being understood that the tread is repeated throughout the circumference of the tire;

FIG. 2 is a front view;

FIG. 3 is a right side view;

FIG. 4 is a left side view;

FIG. 5 is a section view taken along line 5 of FIG. 2;

FIG. 6 is a section view taken along line 6 of FIG. 2;

FIG. 7 is a perspective view of a second embodiment of a tire of our new design, it being understood that the tread is repeated throughout the circumference of the tire;

FIG. 8 is a front view of the embodiment of FIG. 7;

FIG. 9 is a right side view of the embodiment of FIG. 7;

FIG. 10 is a left side view of the embodiment of FIG. 7;

FIG. 11 is a section view taken along line 11 of FIG. 8;

FIG. 12 is a section view taken along line 12 of FIG. 8; and,

FIG. 13 is an enlarged view of a portion of the tread of the embodiment of FIG. 1.

The dashed lines in the drawings show environmental features of the tire and form no part of the following claim.

1 Claim, 13 Drawing Sheets
